Primary Examiner — April Rivas(74) *Attorney, Agent, or Firm* — Paratus Law Group, PLLC(57) **CLAIM**

The ornamental design for a protective hang cover skin for electronic device, as shown and described.

DESCRIPTION

FIG. 1 is a front, top and right side perspective view of a protective hang cover skin for electronic device, showing the claimed design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a front, bottom and left side perspective view thereof;

FIG. 9 is a rear, bottom and right side perspective view thereof;

FIG. 10 is a cross-sectional view taken along line 10-10 shown in FIG. 2; and,

FIG. 11 is a front, top and right side perspective view thereof with a top portion open in use.

The broken lines shown in FIG. 11 depict environment and form no part of the claimed design.

1 Claim, 10 Drawing Sheets(56)
